CLAIM

The ornamental design for an automobile injector cleaner and tester, as shown and described.

DESCRIPTION

FIG. 1 is a front, right, and top perspective view of an automobile injector cleaner and tester, showing my design. FIG. 2 is a rear, left, and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1;

FIG. 10 is a partial enlarged view of an area labeled 10 in FIG. 1;

FIG. 11 is a partial enlarged view of an area labeled 11 in FIG. 1; and,

FIG. 12 is a partial enlarged view of an area labeled 12 in FIG. 2.

The broken lines shown in the drawings depict portions of the automobile injector cleaner and tester that form no part of the claimed design. The dash-dot-dash broken lines encircling portions of the claimed design that are illustrated in enlargements form no part of the claimed design.
